UNITED STATES PATENT OFFICE

ROBERT H. LAWSON, OF PAWTUCKET, RHODE ISLAND, ASSIGNOR TO HEMPHILL COMPANY, OF CENTRAL FALLS, RHODE ISLAND, A CORPORATION OF MASSACHUSETTS

KNITTING MACHINE

Application filed July 7, 1930. Serial No. 468,061.

This invention relates to so-called Lamb or Burson types of knitting machines provided with two opposed banks of needles each mounted in a flat needle bed although the invention is not necessarily and in all respects limited to knitting machines provided with two beds or sets of needles or to knitting machines provided with straight or flat needle beds.

10 In the drawings:

Fig. 1 is a view in end elevation showing a machine of the Burson type with the present improvements applied;

15 Fig. 2 is a plan view of the machine shown in Fig. 1;

Fig. 3 is a vertical sectional view taken through one needle bed and pattern drum for controlling the needles and showing one needle in a neutral position;

20 Fig. 4 is a sectional view taken along the line 4—4, Fig. 3, but omitting the pattern drum;

Fig. 5 is a view similar to Fig. 3 but showing a fragment only of the pattern drum and a needle in a lowered, active position;

Fig. 6 is a view similar to Fig. 5 but showing a needle in a raised, active position;

Fig. 7 is a view of a pattern drum slightly modified with respect to the drum shown in Fig. 3;

Fig. 8 is a plan view showing a single pattern drum and gears for driving the independent sections thereof; and

Fig. 9 is a view partly in section showing the driving connections between the gears, Fig. 8, and the sections of the drum which sections are driven or advanced thereby.

Referring specifically to Figs. 1, 2, 8 and 9 of the accompanying drawings the frame of the machine includes two upright plates or supports 1 which act as bearings for two shafts 2 and 3. Mounted upon the shafts 2 and 3 are drums 4 and 5 which consist of independent sections 6, 7, 8, 9 and 6', 7', 8', 9' independently driven or advanced by means of gears 10, 11, 12, 13 and 10', 11', 12', 13' respectively. The section 6 and gear 10 (Fig. 9) are made fast to an outer sleeve 14 by means of set screws 15 and 16. The drum section 7 is connected to its gear 11 by means

of an inner sleeve 17 and set screws 18 and 19 respectively connecting the drum section 7 and gear 11 to the said sleeve 17 which sleeve 17 passes through and serves as a bearing for the outer sleeve 14. Sleeve 17 surrounds and is supported, for turning movements, by shaft 2 which provides a bearing therefor. Set screws 20 and 21 respectively connect the drum section 8 and gear 12 to the shaft 2 which serves as a bearing for a sleeve 22 to which sleeve the drum section 9 and its gear 13 are connected by means of set screws 23 and 24 respectively.

The described connections between the several drum sections and their gears permit each drum section to be advanced by their gears independently of advancing movements which may be imparted to others of the drum sections. The gears 10, 11, 12 and 13 are independently driven in any suitable manner.

The drum sections 6, 7, 8 and 9 are provided with hubs 25, 26, 27 and 28 through which the before mentioned set screws 15, 18, 20 and 23 pass and by means of which the drum sections are connected to the shaft 2 or sleeves 14, 17 and 22. Spacing collar 29 surrounds the sleeve 14 between the drum section 6 and gear 10 while a corresponding collar 30 surrounds the sleeve 22 between the drum section 9 and gear 13.

Formed integrally with the hubs are spokes or arms 31 (Fig. 3) and connected to or formed integrally with the free ends of the arms are heads 32. The outer or peripheral surfaces 33 of the heads 32 provide seats or radial supports for thin sheet metal or other needle selecting strips 34, 35. Although any desired number of such strips 34, 35 may be used, in the present construction, there are four circularly arranged strips 34 and four similarly arranged strips 35 for each lever 36; but, in order to show the strips 35, two of the strips 34 are omitted from Fig. 3. Lengthwise of the drum sections the strips 34 and 35 are alternately arranged and are provided at or adjacent their ends with extensions or feet 37 and 38 respectively. The feet 37 are received within the slots 39 cut in spacing bars 40 while the feet 38 are

notched as at 41 to seat upon the walls which define and are between the slots 39. The spacing bars 40 are received within longitudinally extending grooves 42 provided in the outer faces of additional, radially extending supporting members 43 integrally or otherwise connected to the hubs, such as 25 of the drum sections. In order to retain the feet 37, 38 of the strips 34, 35 seated 10 within the slots, flanged plates 44, 45 are provided, the flanges 46, 47 of which are received within slots or grooves 48, 49 extending longitudinally of the members 43. At their other ends the plates 44, 45 are provided with inwardly extending flanges 50, 51 received within notches or grooves provided in the strips 34, 35. Intermediate the ends of the plates 44, 45 holes are provided and passing therethrough and through holes in 20 the members 43 are bolts 52, the outer ends of which project through the plates 44, 45 and are there provided with heads 53 and nuts 54 to retain the plates 44, 45 in clamping engagement with the members 43 and the strips 34, 35 seated in position upon the peripheral or outer faces 33 of the heads 32.

As hereinbefore stated two circularly arranged series of strips 34, 35 are provided for each lever 36 and consequently each of 30 the strips 34, 35 serves to space and laterally support the adjacent strips. The levers 36 are provided with upwardly extending arms 55 for a purpose hereinafter to be more fully described and other arms 56, 57 which extend laterally from each side of a rod 58, carried by the machine frame, upon which the levers 36 are supported for rocking movements. Each arm 56 is provided with a downwardly extending toe 59 which seats upon the peripheral edge or surface of a strip 35 while each arm 57 is likewise provided with a downwardly extending toe 60 which latter, however, is so shaped as to be spaced radially somewhat from the peripheral edge or surface of the strips 35 at all times. Projecting laterally from the toe 60 is a lug or toe 61 which seats upon the peripheral edge or surface of a strip 34.

Although the lugs 59 and 60 act as lateral spacing members for the strips 34 which extend radially outward a distance beyond the companion strips 35, additional spacing means may be provided consisting of plates 62 and 63 which extend transversely of the drum sections and are rigidly connected to the frame of the machine as by screws 64. The transversely extending members 62 and 63 are provided with slots as shown which slots provide walls 65 that extend between the strips 34 and serve additionally to prevent the latter from sidewise or lateral displacement.

The strips 35 are provided with stepped formations upon which the toe 59 of each lever 36 seats and the strips 34 are likewise

provided with corresponding formations upon which the lug 61 of each lever 36 seats. Any desired number of steps may be utilized but as herein disclosed, attention being particularly directed to Figs. 3, 5 and 6, five such steps or elevations 66, 67, 68, 69 and 70 are or may be provided upon the strips 35 and corresponding steps or elevations 71, 72, 73, 74 and 75 are or may be provided upon the periphery of each strip 34. The number and relative disposition of the mentioned steps time and control the operations of the needles as will be described.

In Figs. 3, 5 and 6 the arm 55 of a lever 36 is shown as connected to a more or less semi-circular shaped plate 76 by means of a ball and socket connection 77. Each plate 76 is connected as described to a lever 36 and is pivotally mounted upon a pin 78 extending longitudinally of the needle bed. The pin 78 permits the plates 76 to be rocked, when their corresponding levers 36 are rocked, in a manner hereinafter to be more fully described. Opposite the pins 78 the plates 76 are provided with overhanging fingers 79 between which and the body of the plates 76 slots 80 are provided and within the slots 80 are seated for rocking and sliding movements jacks 81 which although termed jacks are connected to the usual needles (not shown) used in machines of the Lamb or Burson type, by means of hooks 82 engaging over butts formed on the ends of the needles. The so-called jacks 81 therefore are, in effect, part of the needles and will be hereinafter referred to as needles or as constituting part of the same. Intermediate their ends the needles 81 are provided with butts 83 extending upwardly and other butts 84 extending downwardly and projecting from the other side or edge of the needles 81. The butts 83, 84 of the needles 81 are adapted to be engaged and actuated, as selected, by cam carrying slides 85 and 86 duplicated at 85', 86' for controlling the needles of the other needle bank as shown in Fig. 2. The specific construction of the cam slides themselves forms no necessary part of the present invention other than that the plurality of cam slides or carriers selectively control the needles 81 in a manner hereinafter to be more fully described and as dictated by the cooperative action of pattern strips 34, 35, levers 36 and plates 76.

Fig. 3 shows a needle 81 in an inactive, intermediate position in which position the butts 83, 84 are not in the path of the advancing cams carried by the cam carriers 85, 86, (Fig. 2). The upper cam carrier 85 is adapted to control the movements of such of the needles 81 as are moved to the intermediate, dotted line position and upper full line position of Fig. 6 while the lower cam carrier 86 is adapted to control the movements of such of the needles 81 as are moved to the intermediate, dotted line position of Fig. 5.

or the extreme lower, full line position of said figure.

During the knitting of the non-fashioned portion of the stocking leg, all of the needles 5 may be moved either to the intermediate, dotted line position shown in Fig. 5 or to the dotted line position shown in Fig. 6 in which positions the cam carriers 85 and 86 as the case may be, act upon the butts 83 or 84 of 10 all of the needles and advance them in a normal manner.

Whenever additional wales are knit in for the purpose of widening the stocking a needle from the opposite, i. e., then inactive 15 needle bank is advanced to knit and in order to control such needle without actuating the other needles of the said other needle bank the center cam carried by one of the cam carriers 85, 86 or 85', 86', as the case may be, 20 is moved to a level to miss the intermediately positioned butts 83 or 84 but not to a position to miss the butt of the single needle referred to which butt, during the mentioned widening course, is moved to the full line position 25 shown in Fig. 5 or to that of Fig. 6. Although obviously the single widening needles may be controlled by cams mounted upon the cam carriers 85, 85' or the lower cam carriers 86, 86', preferably, the upper cam carriers 85 and 85' are utilized for this purpose in which case it is not necessary that the other or lower cam carriers 86, 86' be provided with a movable center cam and as a consequence thereof the needles 81 may be 30 moved to the intermediate, dotted line position of Fig. 5 but not necessarily to the full line position thereof.

Although the order may be reversed or the upper and lower cam carriers be controlled 40 otherwise, preferably, the instep or upper half of the foot of the stocking is knit by controlling the needles 81 through the lower cam carriers 86 and 86' while all the widening, including the widening of the toe, heel and leg and all of the plain knitting of the non-fashioned portions of the ankle and leg are knit by controlling the needles through 45 the upper cam carriers 85 and 85'.

In Fig. 3 the drum section 6 is shown as 50 having been advanced, in the direction of the arrow, to such a position that a level or step 68 provided upon a strip or pattern element 35 is in engagement with the toe 59 of the jack lever 36 and the corresponding needle 81 positioned at an intermediate, inactive level where its butts 83, 84 are not in a position to be actuated by either the upper or by the lower cam carrier. At the same time the toe or lateral lug 61 of a jack lever 36 is 55 shown as resting upon an intermediate level or seat 73 and as a drum section, such as the drum section 6, advances in a counter-clockwise direction as indicated by the arrow, Fig. 3, a vertical or other wall separating the steps 66-70 raises lug 59 and tilts the lever 60

36; while the lug 61, as the drum section advances in the direction of the arrow, merely drops off one seat or level to another. On the other hand when a needle 81 is moved from an upper position, such as that shown in Fig. 6, a lug 61 resting as shown upon the lowermost seat 71 is, as the drum section advances in a clockwise direction indicated by the arrow, raised and the lever 36 is tilted as the toe 59 of a lever 36 drops from the seat 75 or level 70 onto the level 69.

Spacing the jack supporting plates 76 and levers 36 are plates 87 supported and carried by the rods 58, 58' and 78, 78' which rods extend lengthwise of the needle bed and at their ends pass through and are secured to end plates 88, 88' (Fig. 1). The plates 76 are additionally supported and laterally spaced by cam slide supporting plates which are carried by the end plates 88, 88'. The end plates additionally serve to support plates 89, 89' which extend lengthwise of the needle beds and in turn support the slidably mounted cam carrying bars 85, 86, 85', 86'. The end plates 88, 88' and cam bar supporting plates 89, 89' are mounted upon or carried by bars 90, 90' which are made fast to the side plates 1 of the machine frame.

As hereinbefore described the drum 5 is a duplicate of the drum 4 and is made up of independent drum sections 6', 7', 8', 9' corresponding to and directly opposite sections 6, 7, 8, 9 of the drum 4. The drum sections 6', 7', 8' and 9' are connected to their respective driving gears in the same manner as the drum sections 6, 7, 8 and 9 are connected to their respective driving gears as shown in Fig. 9. Opposite to and meshing with the gears 10, 11, 12 and 13 are gears 10', 11', 12' and 13' which latter gears drive or advance the corresponding drum sections 6', 7', 8' and 9'. Furthermore the elements hereinbefore described as associated with and controlling the needle movements of the needles, the active and inactive positions of which are determined by drum 4, are duplicated by elements associated with and controlling the needle movements of the needles, the active and inactive positions of which are determined by drum 5, which duplicated elements or some of them are indicated by corresponding prime reference numerals.

In Fig. 7 is disclosed a somewhat modified construction of drum for supporting the pattern plates 34, 35. The drum section shown therein is modified with respect to the drum shown in Fig. 3 to the extent that the heads 91 corresponding to the heads 32 of Fig. 3, are not integral with the hub of the drum as they are in Fig. 3 but are separate therefrom and maintained in adjustable engagement with the inner edges of the pattern plates 34, 35 by means of bolts 92 at one end in threaded engagement with the hub of the drum 9 at 93 and at their other ends 94 in 130

contact with cup-shaped recesses 95 provided in the heads 91. Heads 96 carried by the bolts 92 serve to permit radial adjustment of the heads 91 and lock nuts 97 carried by the bolts 92 frictionally engage bosses 98 carried by the drum to prevent unintentional turning of bolts 92.

Each of the gears 10, 11, 12 and 13 and consequently their drum sections 6, 7, 8 and 9

10 may be moved circumferentially in either direction of rotation independently of the others, and likewise the gears 10', 11', 12' and 13' and drum sections 6', 7', 8' and 9' are movable independently. Furthermore although 15 the gears 10, 11, 12 and 13 as shown are respectively in mesh with the gears 10', 11', 12' and 13' the sets of gears may be independently driven.

The members 33 and 34 determine the 20 changes in the pattern of the fabric knit by the needles, i. e., they selectively determine, from course to course, the active and inactive positions of the several needles whereby any desired pattern change may be effected 25 whether for the purpose of changing the design or for fashioning or otherwise forming the stocking or other fabric, and for that purpose the pattern controlling elements are uniformly spaced one from another, i. e., the 30 pattern controlling elements 33 are substantially equally spaced one from another laterally, or lengthwise of the drum and the companion pattern controlling elements 34 are likewise substantially equally spaced one from another.

The construction hereinbefore described 35 permits the pattern controlling elements 34, 35 to be so set in the drums that the sections thereof may be moved or advanced freely 40 although the said drum sections abut one another. Furthermore each element 34, 35 may be readily removed from its seat in a drum section without disturbing the adjacent pattern elements. In addition to the advantages 45 inherent in the present construction and as hereinbefore recited the pattern elements 34, 35 may be and often are slightly undersize which is rendered possible by the provision of the lateral supports for the said elements 50 which lateral supports consist of the walls 65 and companion pattern elements.

Although in the foregoing description the parts and combinations thereof have been specifically described, the invention is not 55 limited to such specific constructions except as required by the scope of the claims appended.

I claim:

1. In a knitting machine, a needle bed and 60 needles mounted therein, oppositely extending butts provided upon the needles which butts are adapted to be engaged by cams,

means for positioning the needles so that the needles or some of them will be in such a position that the butts extending in one direction may be engaged by cams, or in such a position that the other mentioned butts may be engaged by cams, or for positioning some at least of the needles where they will be idle.

2. A pattern drum having pattern controlling elements removably mounted thereon, slotted means provided upon the drum, some of the pattern controlling elements provided with means removably seated within the slots of the aforesaid means and others of the pattern controlling elements removably seated upon the walls defining the aforesaid slots.

3. A pattern drum having pattern controlling elements removably mounted thereon, slotted means provided upon the drum, some of the pattern controlling elements provided with means removably seated within the slots of the aforesaid means and others of the pattern controlling elements removably seated upon the walls defining the aforesaid slots, other means adapted removably to retain the pattern controlling elements in position.

4. A pattern drum provided with independently movable sections, and means for independently moving the sections in either of two directions.

5. A pattern drum provided with independently movable sections, means for independently advancing the sections, a shaft and sleeves each independently driven and connected to a drum section whereby the latter are advanced independently of the other sections, in combination with cam-formations carried by the pattern drum and needles, each needle being individually controlled by the said cam formations.

6. A pattern drum composed of independently movable sections, a centrally disposed shaft connected to one of the sections, sleeves rotatably mounted upon the said shaft and connected to others of said sections, driving means consisting of a plurality of gears, the shaft and sleeves each independently connected to and driven by a gear whereby the drum sections to which the shaft and sleeves are connected are advanced independently of the other sections.

7. A pattern drum provided with independently movable sections, each of said sections adapted to be moved independently of the others and in either of two directions.

8. A pattern drum composed of independently movable and abutting sections, and a plurality of laterally spaced pattern controlling elements mounted in each drum section.

ROBERT H. LAWSON.
